UNITED STATES PATENT OFFICE.

WILLIAM H. FOYE, OF SEATTLE, WASHINGTON.

ELEVATOR SAFETY DEVICE.

Application filed April 17, 1922. Serial No. 554,013.

To all whom it may concern:

Be it known that I, WILLIAM H. FOYE, a citizen of the United States of America, and resident of the city of Seattle, in the county of King and State of Washington, have invented certain new and useful Improvements in Elevator Safety Devices, of which the following is a specification.

My invention relates to elevators and particularly to the provision thereon of means whereby the operation of the elevator is normally prevented during the time when the shaft gates are opened and by which the opening of the said gates cannot normally be accomplished except when the elevator is within permissible limits of variation in the level.

Another object is to provide a safety device of the type stated, which will not at any time affect the operability of the elevator except when it is near the landing positions and the shaft gate is open, thus interfering not at all with movement of the elevator within these relatively restricted landing zones.

Another object of my invention is to provide a safety device which will not be wrecked by movement of the elevator up or down while the shaft gate is open, whether this be due to a slow creeping action or stretch of suspenders by change of loading, or operation with a shaft gate incompletely closed.

The object of the invention, broadly stated, is thus to provide safety means which will prevent accidents due to operating the elevator when the gates may be open, and also to prevent opening of the gates while the elevator is within a zone near to above or below the proper level.

My invention consists in certain attachments which are applied to the elevator car and to the shaft gates, whereby the above results may be secured.

The object of my invention is to provide means which will secure the above results and to have such means of a simple and dependable character which do not cost too much to install and which are not liable to get out of order.

The particular features which I believe to be new and upon which I desire to obtain a patent will be hereinafter described and then particularly defined by the claims.

In the accompanying drawings I have shown my invention applied to an elevator in the type of construction which I most prefer to use.

Figure 1 is a side view showing the exterior of a portion of an elevator car and the shaft gate which operates in conjunction therewith.

Figure 2 is a horizontal section taken through the shaft gate and associated parts of the car.

Figure 3 is a vertical section through the car and the shaft gate, showing the relationship of the various parts.

Figure 4 is a view similar to Figure 3 showing the parts in a different position.

Figure 5 is a sectional elevation similar to Figure 3, in which however, the parts have been mounted in somewhat different relationship.

Figure 6 is a detail section showing the type of construction preferred for mounting the stop pin and its relation with the stop bars.

Figure 7 is a side elevation of a part of a car and one shaft gate showing a simplified form of the device, which may be satisfactory for some conditions, and Figure 8 is a diagram showing the electrical connections employed in the device illustrated in Figure 7.

The chief features of my invention concern the use of a stop finger in combination with a stop bar or bars, carried respectively one by the car and the other by the shaft gate. Of the stop bars, one extends vertically and is positioned to engage the stop finger to prevent opening of the shaft gate, unless the car lies within a predetermined zone of level, while the other stop bar extends horizontally and is movable towards and from the car under control of the power controller and is so positioned vertically as to cover the zone occupied by the stop finger when the car is within the permissible limits of level for landings.

In the accompanying drawings the device as illustrated has the stop finger upon the gate and the stop bars on the elevator car. The disposition of these parts shown is that which is preferred, as the duplication required for the various landings is of the simplest set of mechanisms, namely the stop finger.

With the above elements of my invention is or may also be employed a mechanism whereby one of the stop bars is controlled in position and operation from the power controller. In some cases the stop finger may be employed in connection only with one of the stop bars. This may be either one of the stop bars, the choice depending upon the result desired.

10 In the drawings 1 represents a portion of an elevator car and 2 a shaft gate by which ingress and egress from the car is controlled. The gate is, of course, duplicated for each landing. The shaft gate 2 in the preferred 15 form of construction has a stop pin mounted thereon, while the car has a stop bar or stop bars mounted so as to coact with the stop pin to prevent opening of the shaft gate unless the car is within predetermined limits 20 of level with relation to the landing. The stop pin 3 carried by the gate, projects towards the car. Its length is sufficient that it will not engage any part of the car as the shaft gate is opened or closed, excepting the 25 stop bars which have been provided for this purpose and which form a part of my invention.

In the more complete form of my invention two stop bars are used, one extending 30 vertically and being fixed in position with relation to the car. The other extends horizontally and is movable towards and from the car under the control of the power controller by which the car is operated. Either 35 of these may be omitted if its function may be dispensed with. The vertical stop bar as herein illustrated consists of an angle bar 4. The essential feature of this bar is the outwardly projecting flange 40. This 40 flange is interrupted in the middle portion of its length to form a gap 41 of a width corresponding with the variation in level of the car which is permissible in making a landing. The flange 40 projects from the 45 car sufficiently to securely engage the stop pin 3 carried by the gate, whenever the stop pin 3 is at a level corresponding with the vertical extent of said flange 40. In other words, the flange 40 will prevent opening 50 the gate whenever the car is positioned within a certain limit of level which extends materially above and below the landing, unless the car is within a small limit 55 wherein there is slight variation between the level of the car floor and of the landing.

A horizontally extending stop bar or plate 5 is mounted upon the car so as to be movable towards and from the same and is of such a width and so positioned that it covers the space represented by the notch 41 in the vertical stop bar 4. Normally this stop plate 5 is held close up against the side of the car, in which position it will not engage the stop finger 3 or prevent opening of the 60 gate. If, however, it be moved outward any 65

material distance, its end extending across the gap 41 in the stop bar 4, will be engaged by the stop finger and prevent opening of the shaft gate. The position of the stop bar 5 is controlled by the power controller through the operation of which the car is moved up or down.

A simple and efficient manner of mounting the plate 5 is to support the same upon vertical arms 6. These arms may be of 75 spring character secured by their opposite ends, as 60, to the car whereby they may be forced outward without too much resistance and yet when unrestrained will be held close up against the side of the car. The same result may, of course, be secured by pivoting the bar 6 and using springs as 61 to hold the arms and the stop bar 5 against the side of the car. The manner of holding this bar for movement is immaterial.

The stop bar 5 is of a length corresponding with or not less than the amount of travel given the shaft gate in opening it, so that the stop finger 3 will never travel beyond the outer end of the bar 5. The stop finger 3 lies just beyond and close to both the stop bars 4 and 5 when the shaft gate is closed, so that the up and down movement of these stop bars in the operation of the car will not interfere with the stop finger 3.

It may happen at times, through the slow up or down movement of the car after it has been stopped, due to applying or removing its load or from other causes, that the stop finger 3 gets above or below the stop bar 5. In this position if the shaft gate be closed the stop finger 3 will engage the side of the flange 40 above or below the gap 41. To provide for such contingencies and to avoid any injury to the parts, the stop finger 3 is pivoted upon a pin as 30 which projects from the edge of the shaft gate in the direction of movement of the gate while opening and closing.

This pin is also of such length as to permit horizontal movement of the stop finger 3 sufficient to accommodate the conditions above referred to, wherein the pin engages the inner face of the flange 40. The pivoting of the finger 3 is chiefly for the purpose of permitting rocking of the finger so that it may pass the stop bar 5 when the latter is projected, as it will be when the power is applied to operate the car. When this happens the finger 3 will be swung to one side and then be immediately brought back to its normal position by means of a spring, as the spring 31 which is shown in Figure 6, or the spring 32 as shown in Figures 1, 3, 4 and 5. By reason of this manner of mounting the stop pin no harm will occur in case there has been a change in level of the car while the shaft gate is open or when the car is operated past a closed shaft gate. The stop pin will slide along the outer surface of the

flange 40 until it reaches the end thereof and then be returned to its normal position by the action of the springs 31 and 32.

The horizontal stop bar 5, as has been stated, is controlled in its position toward or from the car by the position of the power controller for the car. A convenient means for doing this is illustrated in Figures 3, 4, and 5. The operating handle through which the power is controlled is therein shown as provided with a disk or plate 7 which carries two horizontally projecting pins 70. These two pins are at the same level when the operating handle is in neutral position. They also, in such position, bear against the upper side of a horizontally extending pin 71 which is carried by a lever 72. The lever 72 is carried by a rod as 73 which extends lengthwise of and between the stop bar 5 and the side wall of the car. The rod 73 also has cam levers or blocks as 74, of such shape that when the rod 73 is turned, the rod and the stop bar 5 which is connected therewith will be moved outward from the side of the car. This carries the rod towards the outer part of the gap 41 or into a position where it will be engaged by a stop pin 3. The stop bar 5 will not be held in this position except when the controller has been turned to a position to apply the power.

It is evident that such action will occur whenever the controlling lever 7 is thrown in either direction from its neutral position. Such action will cause one or the other of the pins 70 to depress the lever 71 and thus throw the stop bar 5 outwardly. The spring action of the plates 6 will serve to return the stop bar 5 and lever 72 into its normal position close against the car, wherein the finger 3 is free to move. It follows from the above construction that whenever the finger 3 is opposite the face of the stop bar 5, as it would be if the shaft gate be open any material distance, the power controlling lever cannot be moved into such position as will apply the power to the car and that therefore, the car cannot be raised or lowered while the shaft gate is open.

In Figures 3 and 4 the action of the power controlling device upon the stop bar 5 is direct. In figure 5 is shown a construction wherein the level of the stop bar 5 has been changed, being placed at some distance above the controller. In this case a slightly modified construction is employed. The cam lever 72 of Figure 3 is changed in its construction. This change is chiefly in the omission of the horizontally extending rod 71 and the substitution therefor of a link as 8 which extends up or down as may be necessary, to a slide 80 which is provided with a ledge 81 of sufficient horizontal extent to engage both of the pins

70 carried by the controller. A spring as 82 serves to return these parts to normal position.

In connection with the above parts a circuit breaker may be employed, controlled by each of the shaft gates. This may conveniently be in the form of a jack consisting of a plug or finger carried by the shaft gate and inserted when the gate is closed between the two contact members. Such a finger is shown at 9 in Figures 1 and 7 and the contact members at 90. These contact members are placed in series in one side of the power circuit. Such a device may be used as an additional safeguard to entirely cut the power off from the car when the gate is opened. Its use is however optional.

Such a circuit breaker controlled by the shaft gate may be employed with one only of the stop bars which is described. In the device as shown in Figure 7 this has been done, the vertical stop bar 4 being the one employed. By using a device of this character the gate cannot be opened except when the car is at the proper limit of level and the car cannot then be started until the gate has been closed. This may be sufficient safeguard to satisfy some conditions.

What I claim as my invention is:

1. A safety device for elevators comprising a vertically extending bar and a horizontally projecting finger carried one by the car and the other by the shaft gate in positions to engage to prevent opening of the said gate, said bar having a recess positioned to permit passage of the finger when the car is within the permissible variation from exact level with the landing, and a third safety member carried by the car and movable by the power controller into position to lock the shaft gates against opening when the power is on and engageable by the shaft gate to prevent placing the controller in power-on position when the gate is open.

2. A safety device for elevators comprising a vertically extending bar and a horizontally projecting finger carried one by the car and the other by the shaft gate in positions to engage to prevent opening of the said gate, said bar having a recess positioned to permit passage of the finger when the car is within the permissible variation from exact level with the landing, a third safety member carried by the car and projectable into the path of the shaft gate to prevent its opening, and means whereby this third member is controlled by the power controller.

3. A safety device for elevators comprising a vertically extending bar and a horizontally projecting finger carried one by the car and the other by the shaft gate in positions to engage to prevent opening of the said gate, said bar having a recess positioned to permit passage of the finger when the car is

within the permissible variation from exact level with the landing, a horizontally extending bar mounted upon a common base with said vertical bar and in alinement with the gap in the vertical bar, said horizontal bar being movable toward and from the car to thereby obstruct and free said gap for the passage of said finger, and means for controlling the position of said horizontal bar 10 from the power controller.

4. A safety device for elevators comprising a stop finger carried by the shaft gates, a horizontal bar carried by the car in position to be alined with said stop finger when the car is leveled with the landing, and means controlled by the power controller to move said bar into the path of said finger to thereby prevent opening of the gate when the controller is in power-on position.

20 5. A safety device for elevators comprising a stop finger and a horizontally extending bar mounted for movement toward and from the car, one of said parts being carried by the gate and the other by the car and vertically positioned to be in horizontal alinement when the car is leveled with the landing, and means controlled by the power controller for moving said bar into the path of travel of the finger when the controller is in power-on position.

30 6. A safety device for elevators comprising a stop finger carried by the shaft gate and projecting towards the car, a vertically extending stop bar carried by the car in position to be engaged by the stop finger when the shaft gate is opened, said bar having a gap adapted to permit passage of the finger when the car is properly leveled, a horizontally extending bar carried by the car and movable towards and from the car, said latter bar being of a width and positioned to close said gap in the vertical stop bar when held outwardly from the car and of a length to cover the limit of backward movement of said stop finger, and means controlling the outward and inward movement of the horizontal stop bar from the power controller.

40 7. A safety device for elevators comprising a stop finger carried by the gate and projecting towards the car, said finger being pivoted to swing up and down, means for yieldingly holding said finger in horizontal position, a horizontally extending stop bar carried by the car and extending from near said finger when the gate is closed to beyond the limit of travel of said finger when the gate is open, said bar being mounted to be moved towards and from the car, and means controlled by the power controller to cause such movement of the bar.

50 8. A safety device for elevators comprising a stop finger carried by the gate and projecting towards the car, said finger being pivoted to swing up and down, means for yieldingly holding said finger in horizontal

position, a horizontally extending stop bar carried by the car and extending from near said finger when the gate is closed to beyond the limit of travel of said finger when the gate is open, said bar being mounted to be moved towards and from the car, a lever mounted on the car and adapted to move said stop bar outwardly from the car, a pivoted controller lever on the car and fingers carried by said controller lever and engaging said lever to throw said stop bar outward into stop position when the controller is placed in power-on position.

90 9. In a device of the character described, a stop pin carried by the gate and extending horizontally in the direction of movement of the gate in opening, a stop finger pivoted upon said pin, a spring acting to normally hold said finger extended horizontally towards the car, and a safety bar carried by the car and extending along the path of movement of said stop pin as the gate opens, and means controlled by the power controller to move said safety bar outward into the path of movement of the stop pin before applying the power.

95 10. In a safety device for elevators, a stop pin mounted upon the gate and extending in the direction of movement of the gate in opening, a stop finger pivoted upon and movable lengthwise of the pin, a spring normally holding said finger toward the inner end of the pin and projecting towards the car, and a vertically extending stop bar carried by the car in position to be placed in the path of said stop finger in opening the gate when the car is adjacent the proper landing level, said stop bar having a gap for the free passage of the stop finger when the car is properly leveled, and a horizontally placed stop bar projectible into the path of said finger when the gate is opened, and means for so projecting said stop bar when the power is on.

110 11. In a safety device for elevators a stop pin mounted upon the gate and extending in the direction of movement of the gate in opening, a stop finger mounted to slide and turn upon said pin, and a stop bar mounted upon the car in position when the car is properly leveled to be alongside of the path of movement of the stop finger as the gate is opened, and means for moving said stop bar into position to occupy said path of movement of the finger when the power controller is moved to apply power.

115 12. A safety device for elevators having means for preventing opening of the shaft gates within a limited range of level of the car above and below the permissible landing level and means permitting closing of the shaft gates at all levels.

120 13. A safety device for elevators having means for preventing opening of the shaft gates within a limited range of level of the

car above and below the permissible landing level, means permitting closing of the shaft gates at all levels, and means for preventing the application of power when the gate is open.

14. A safety device for elevators comprising two members carried one upon the car and the other upon the shaft gate and positioned to be normally in adjacent but non-engageable positions as the car moves past the gates and to engage by the opening of the gate, one of said members having a considerable vertical extent and a very limited horizontal extent in the direction of the opening and closing movement of the gate and having a gap intermediate its ends for the passage of the other member, said other member being of slight extent in the direction of the opening and closing movement of the gate and adapted to pass freely through said gap.

15. A safety device for elevators comprising two members mounted, one upon the car and the other upon the shaft gate, said members being positioned to occupy interfering planes when the gates are opening and closing and to normally occupy closely adjacent non-interfering narrow paths during vertical movement of the car, one of said members being adapted to yield when engaging the other by relatively vertical movements, the other being of relatively considerable vertical extent and having a gap intermediate its ends for the free passage of the complementary member during opening and closing of the gate.

16. A safety device for elevators comprising two members mounted, one upon the car and the other upon the shaft gate, said members being positioned to occupy interfering planes when the gates are opening and closing and to normally occupy closely adjacent non-interfering narrow paths during vertical movement of the car, one of said members being adapted to yield when engaging the other by relatively vertical movements, the other being of relatively considerable vertical extent and having a gap intermediate its ends for the free passage of the complementary member during opening and closing of the gate, said yielding member also being yieldingly mounted to have a limited bodily movement in the direction of movement of the gates whereby contact with the

other member will not prevent proper closure of the gate.

17. A safety device for elevators comprising a vertically extending bar and a horizontally projecting finger carried, one by the car and the other by the shaft gate and positioned to be engaged to prevent opening of said gate when the car is adjacent to its proper landing level, said bar having a gap permitting transverse passage of the pin when the car is within permissible range of landing level, said pin being yieldingly mounted for limited movement transversely of the stop bar.

18. A safety device for elevators comprising a vertically extending bar and a horizontally projecting finger carried, one by the car and the other by the shaft gate and positioned to be engaged to prevent opening of said gate when the car is adjacent to its proper landing level, said bar having a gap permitting transverse passage of the pin when the car is within permissible range of landing level, said pin being yieldingly mounted for limited movement transversely of the stop bar, the pin and the top and bottom faces of the gap in the said bar having beveled surfaces adapted to engage to laterally move the pin on the closing movement of the door.

19. A safety device for elevators comprising a vertically extending stop bar having a gap therein and a stop pin, one carried by the car and the other by the shaft gate, said pin being positioned to register with and pass through said gap when the car is within permissible limits at the landing positions and being mounted for yielding movement sufficient to permit locking closure of the shaft gate in case the pin should engage the stop bar in closing the gate.

20. A safety device for elevators comprising a stop bar having separated upper and lower sections forming an intermediate gap and a stop pin mounted for yielding vertical swinging and limited yielding movement in the direction of the opening movement of the shaft gate, said stop bar and pin being carried one upon the car and the other upon the shaft gate and movable closely adjacent each other by the travel of the car.

Signed at Seattle, King County, Washington, this 10th day of April, 1922.

WILLIAM H. FOYE.
